DESIGN FOR A DRESS BUCKLE

Harris J. Lipman, New York, N. Y.

Application October 31, 1933. Serial No. 49,616

Term of patent 3½ years

To all whom it may concern:

Be it known that I, HARRIS J. LIPMAN, a citizen of the United States, residing in New York city, in the county of New York and State of New York, have invented a new, original, and ornamental Design for a Dress Buckle, of which the following is a specification, reference being had to the accompanying drawing, forming a part hereof.

Of the drawing:

Fig. 1 is a front perspective view of a dress buckle, showing my new design; and

Figs. 2 and 3 are perspective views showing the two parts of the buckle separated from each other.

I claim:

The ornamental design for a dress buckle, as shown and described.

HARRIS J. LIPMAN.
